BOTTLE HOLDER

Henry K. Powell, Chicago, Ill., assignor to Morris Paper Mills, Chicago, Ill., a corporation of Illinois

Application May 5, 1939, Serial No. 271,827

8 Claims. (Cl. 229—52)

This invention relates to improvements in containers or receptacles, of the collapsible or knock-down type, which are adapted for the packaging and holding of a plurality of bottles or similar articles in a manner such that they are retained securely and may be carried, as a unit, with ease and convenience.

This application is a continuation in part of my United States applications Serial No. 196,230, filed March 16, 1938, and Serial No. 206,127, filed May 5, 1938, Patent No. 2,206,918 having been granted on the last mentioned.

A general object of the invention is the provision of such a container which may be manufactured very economically from paper board or similar inexpensive sheet material with minimum waste, and in a form such that in its collapsed or knocked-down condition it occupies relatively small space, so that it may be conveniently packaged for storage or shipment, and yet may be set up at the point of use very quickly and easily by simple hand operations, without requiring any special equipment or additional fastenings.

Another object of the invention is the provision of such a container which will retain a plurality of bottles very securely against rattling or falling out, yet in a disposal such that they may be displayed or seen with facility, and may be removed, one or more, when desired, without involving any mutilation, dismantling or unfolding of the device.

Yet another object is the provision of such a container which, after being set up, will retain its set-up form, even after some or all of its contents have been removed, ready to receive the bottles again after they have been emptied, thus forming a convenient repository for them and a means for conveniently packaging and returning them to the place of purchase.

A particular object of the invention is the provision of a receptacle having the characteristics mentioned above and which is of a construction that permits its being manufactured of fairly light paper board and yet have the very considerable amount of strength necessary to support the weight of a half dozen bottles of beverages or the like so as to function as a carrier for same.

Yet another object is the provision of a container having the characteristics specified above and which does not project or extend materially beyond the base area of its assembled contents, thus permitting a plurality of the filled packages to be packed in cases or trays of the standard sizes ordinarily used for the handling or trans-

portation of a dozen or two dozen of the bottles involved.

Another object is the provision of a construction for a bottle holder or the like, comprising a collapsible paper board body member and a separately preformed handle of stiff wire or the like, and including features for facilitating the interlocking of the handle with the body member without requiring any reforming of either of them.

Yet another object is the provision of a bottle carrier having the characteristics above specified and which affords a suitable play or flexibility for the handle relative to the paper board body portions, thereby relieving the latter of stresses which might tear it from the handle when the package is swung or shifted while suspended by the handle.

Other and further objects of the invention will be pointed out or indicated hereinafter, or will be apparent to one skilled in the art upon an understanding of the invention or employment of it in use.

For the purpose of aiding in an explanation of the invention I show in the accompanying drawings forming a part of this specification, and hereinafter described, various forms in which it and its several features may be embodied. It is to be understood, however, that these are presented merely for purpose of illustration, and hence are not to be construed in any fashion for the purpose of limiting the appended claims short of the true and most comprehensive scope of the invention in the art.

In said drawings:

Fig. 1 is a perspective view of one form of container embodying the invention, the device being shown in its set-up condition and ready for reception of its contents, and representing it as viewed from a position at one end and slightly above it;

Fig. 2 is a perspective view of the same container with its contents of six bottles assembled in it;

Fig. 3 is a plan view of the blank sheet material from which the body member of the receptacle illustrated in Figs. 1 and 2 is made, showing same before any folding has been done;

Fig. 4 is a plan view of the same blank showing it after marginal portions have been folded inwardly and secured in place as by adhesive;

Fig. 5 is a perspective view showing the body member in its completed form and in a partially collapsed condition;

Fig. 6 is a sectional view serving to illustrate

how the preformed wire handle is attached to and interlocked with the body member illustrated in Fig. 5;

Fig. 7 is a perspective view of a modified form of container embodying the invention, same being shown in its set-up condition and ready for reception of its contents;

Fig. 8 is a perspective view of a girth or retainer member employed as a part of the device illustrated in Fig. 7, same being shown on a somewhat larger scale and in a collapsed or flat folded condition;

Fig. 9 is a perspective view of a second modified form of container, showing same in its set-up condition with the exception of one of the end strips or retainer members, which is shown in its flat condition; and

Fig. 10 is a detail representing the lower end portion of yet another modified form of container embodying the invention, the modified feature residing in the lower end construction here illustrated.

In the retail sale and distribution of beverages and similar commodities which are put up in bottles or the like, it is a matter of considerable difficulty to package a plurality of such bottles in a manner such that they will be retained securely and yet may be carried conveniently as a unit by the purchaser. The present invention is designed to meet the need for an economical and convenient receptacle which may be used for this purpose. I further have in view the importance, to the retailer or bottler, of having the empty bottles returned to him, and in order to facilitate and encourage such returns, I provide a receptacle which is not in any fashion mutilated or harmed by the removal of its original contents, and which consequently is adapted to function as a convenient means for use by the purchaser as a repository for the empty bottles and for their return to the place of purchase. It is quite essential that the cost of such containers to the bottler or user be very low, but at the same time, in view of the fact that the weight of a half dozen bottles of beverage is quite considerable, it is likewise essential that the containers possess very substantial strength. The present invention provides a container which meets these requirements very effectively, and the nature of it will be most quickly ascertained from the following detailed description of the illustrative embodiments shown in the drawings.

In Figs. 1 and 2 I illustrate an embodiment of the invention consisting of a receptacle designed to accommodate six bottles of uniform size, and for an explanation of same, reference is made first to Fig. 3, which represents the blank from which the body member of the receptacle is formed. This blank is cut from a suitable sheet material, such as paper board having the necessary strength and proper stiffness, and is in the nature of an elongated strip or sheet slotted or creased to form a bottom panel 10 having side panels 11 and 11' extending from its opposite side margins and susceptible of being flexed to upstanding positions along crease lines a. The side panels are also subdivided by transverse fold creases b, g and p, and slotted at D to sever three sides of tabs 12, which may be swung inwardly on the crease lines c to provide apertures D' (see Fig. 1) through the upper portions of the side panels. These apertures extend across the greater portion of the width on the side panels. On the longitudinal medial line of the bottom panel 10 are formed two elongated holes E, and

handle holes F and F' are provided in similar relationship on crease lines g which define the inner limits of flap portions 11a and 11b at the ends of the blank.

5 The blank is also creased or scored longitudinally along lines h at an appropriate distance from its opposite side margins, to provide margin strips adapted to be folded inwardly upon the adjacent surface portions of the bottom and side 10 panels. These margin strips are wide enough to overlap the end portions of the slots D and hence are cut out at J so as to conform to them. The margin strips are also slotted transversely at K in alignment with the fold creases b and may be 15 likewise slotted at the ends of creases p, and they are scored obliquely on lines L extending diagonally from the corners of the bottom panel 10.

After the blank has been thus formed, which 20 may be done in a single blanking operation, an adhesive is applied to the portions of the margin strips which are marked with stippling in Fig. 3, and the margin strips are then folded inwardly along the score lines h, into the relationship shown in Fig. 4, and pressed down flat upon the 25 adjacent portions of the bottom and side panels, so that the parts bearing the adhesive are secured in that relationship. Accordingly, there are thus provided end strips 16 which overlie the 30 end portions of the bottom panel and which remain integral with the end margins thereof but otherwise are free of it; and along both margins of the side panels are thus provided reinforcing strips 15 which are adhesively secured to them. 35 It will be observed that these reinforcing strips extend continuously along the ends of the apertures D'.

After the margin strips have thus been folded and secured in position, the outer portions of the 40 side panels are bent inwardly along the crease lines b until they come flat against the subjacent portions of the sheet, the notches K being provided to facilitate such bending. The parts are so proportioned that this will bring the crease 45 lines g into register, with the flap 11a overlapping a portion of the side panel 11' inwardly beyond its crease line g, and the flap 11a is fastened to the side panel 11' in that relationship by the adhesive. Thus the handle holes F are brought 50 into superimposed register with the handle holes F'.

This completes the body member of the receptacle, in the form illustrated in Fig. 5, excepting that as here illustrated the device is not in its 55 completely flattened or collapsed condition, wherein upper portions of the side panels rest flat upon the bottom panel 10. It is in this flat collapsed condition that the body members are stacked and packaged for shipment.

For use with this body member there is provided a preformed handle which may be made of stiff metallic wire, in the form illustrated in Fig. 6, same comprising a bail portion 20 having its opposite ends arranged as parallel legs, and journal portions 20a extending in alignment toward each other from the ends of the bail portion. The spacing of the outer ends of the journal portion, or the legs of the bail portion, corresponds with the spacing of the handle holes F. This handle is attached to and interlocked with the body member in the fashion illustrated in Fig. 6. One of the journal portions 20a is inserted through the handle hole at one side of the body member, and the body member is bowed or 70 arched sufficiently to permit the inner end of the

opposite journal member 20a to be inserted through the opposite handle hole, substantially as shown in said figure. The holes E accommodate the entry of the journal portions 20a, and after both journals are thus inserted, the body member is released so as to spring back to its flat form, thus bringing the handle holes F out to the leg portions of the bail and securely locking the handle to the body member.

It is thus to be observed that the handle is attached to the body member by very simple manual operations which may be performed at the place where the receptacle is to be put into use and without requiring any special equipment. To complete the setting-up of the receptacle, the sides of the body member are pressed inwardly at the crease lines b (see Fig. 5), or the connected ends of the side panels drawn upwardly by means of the handle thus swinging the side panels inwardly along the crease lines b and upwardly along the crease lines a, until they assume the relationship illustrated in Fig. 1. To accommodate this operation, the holes E permit the journal portions of the handle to pass through the bottom section, and the crease lines p facilitate the flexing of the upper parts of the side panels relative to the intermediate parts thereof. At the same time, by virtue of the freedom of the end strip portions 14, and the gores extending to the diagonal scorings L at their ends, the said end strips are caused to swing upwardly away from the bottom panel 10, until they reach positions approximately perpendicular thereto. In the upstanding positions of the side panels, the triangular gore portions between the crease lines a and score lines L rest flat against them so that the side panels support the end strips in their upright positions and the end strips brace the side panels and reinforce the bottom panel against sagging or bowing downwardly.

Being thus set up, the receptacle is ready to receive its contents, in this instance six bottles, which the device is designed to accommodate in two rows of three each. The height and width of the side sections are selected with reference to the height and diameter of the bottles, so that the positions of the apertures D' are below the tops of the bottles and the length of said apertures is less than the aggregate maximum diameters of the three bottles. Accordingly, in order to insert the bottles, the tabs 12 are swung inwardly along the crease lines c, and the bottles are inserted downwardly, bottom first, through the apertures D' until they stand upright on the bottom panel 10. The first two bottles inserted through each aperture are moved to the opposite ends of the aperture, where they come up against the narrow panel portions 11c. The third bottle of each row is then inserted between the two end bottles, thus completing the package in approximately the form illustrated in Fig. 2.

With the package so assembled, the bottles are retained by the end strips 14 against sliding off of the bottom panel, and are retained by the side panel portions 11c against toppling out of the ends of the receptacle. The dimensions of the receptacle are so chosen that the bottles may be thus inserted freely, but when the package is supported by the handle, the traction of the weight of the bottles upon the side panels causes their upper portions to swing inwardly somewhat, thus exercising a clasping or cramping action against the outer sides of the bottles

and holding the opposite rows of bottles in close contact with each other or against the intervening tabs 12. Thus when the package is carried, the bottles are effectively held against rattling and securely retained against withdrawal.

When carried by the handle, the body member is free to swing on the journal portions 20a, thereby relieving the paper board material of stresses which might tend to tear or weaken it where the handle is connected. Also, the handle may be swung laterally or pushed downwardly to a position where its bail is below the tops of the bottles, so as to permit another similar package to be supported on the tops of the bottles.

In order to remove one or more of the bottles, the package is set down upon its bottom, and thereupon the intermediate bottles may be withdrawn upwardly through the apertures D'. Then any of the end bottles may be moved laterally in the aperture D' sufficiently to clear the adjacent portion 11c, whereupon the bottle may be withdrawn upwardly through the aperture.

It is to be observed that the removal of one or more of the bottles does not involve any dismantling, mutilation or unfolding of the receptacle in any fashion, and as a consequence the receptacle may remain in its complete set-up condition, ready to receive the empty bottle or bottles. It thus serves as a convenient repository in which the purchaser can store the empty bottles and then may be used for returning them to the place of purchase. Likewise, if the returned receptacles are in good condition, they may be collapsed for conservation of storage space and subsequently again set up and reused by the bottler or the retailer for the packaging of another half dozen full bottles. When a body member is no longer fit for use, however, the handle may be detached and preserved for use on another body member, a single handle thus serving an infinite number of packages.

In addition to the various advantages specifically mentioned above, it is to be noted that this invention provides a body member which may be manufactured very economically and yet have the requisite strength, inasmuch as the reinforcement provided by the reinforcing strips to the slender portions, such as 11c, permits the use of comparatively light paper board. Moreover, the setting-up operation is very simple inasmuch as the body member is made all in one piece and the end strips 14 are automatically positioned by the flexing of the side sections to the set-up positions. The receptacle does not project to any material extent in any direction beyond the group of bottles which it contains, and hence a plurality of these packages may be packed in cases or trays of the same size as are customarily used for transporting the bottles in two dozen or three dozen lots. Although the contents of the receptacle are securely retained, as above pointed out, nevertheless they are amply exposed to permit its being ascertained at a glance that the package is complete, or, in the course of consumption, how many of the bottles have been emptied.

In Figs. 7 and 8 is illustrated a similar container having a somewhat modified construction. As in the form first described, the body member is formed as an integral strip or blank of paper board, with a bottom section 110 and side sections 11 and 11' which are flexible to upstanding positions relative thereto along crease lines a. The

side sections are connected to each other at their upper ends, as above described, and slotted to form the tabs 12 and bottle receiving apertures as above described. They are also provided with the marginal reinforcing strips 15, and they are creased transversely at *b* so as to permit their upper portions being collapsed to a flat folded position against their lower portions and the bottom section 110.

The bottom section, however, does not have the integral end strips and in lieu thereof a girth or retaining member is employed, same being of the form illustrated in Fig. 8, where it is designated generally by the reference numeral 30. It is formed as a strip of paper board with its ends connected so as to provide a continuous band, and it is creased transversely at 30*d*, so as to have a quadrilateral form when in its set-up condition, as shown in Fig. 7, with side strip portions 30*a* and end strip portions 30*b* and with flap extensions 30*c*, which are flexible inwardly along crease lines 30*e*, so that they will fit between the opposite side panels 11 and 11' and rest flat upon the bottom section 110, as shown. This construction is claimed in my Patent No. 2,284,682, granted June 2, 1942. The body member is provided with a handle 20, as of the type above described.

A second modification is illustrated in Fig. 9. Here the body member is formed as a continuous strip of paper board or the like, creased transversely to form a bottom panel 210, and the opposite side panels 11 and 11' which are conjoined thereto along crease line *a*. These side panels are connected to each other at their upper ends, as above described, and they are also creased transversely at *b* to permit their being collapsed to the flat folded form as above described. They are also provided with the bottle receiving apertures and tabs 12 in their upper portions, and with the marginal reinforcing strips 15, as above described. The end strip portions 214 remain integral with the bottom section and are foldable to upstanding positions on crease lines *h'* and retained by sheet metal stay members 40, as more fully explained in my Patent No. 2,206,918, granted July 9, 1940.

In Fig. 10 is illustrated a further modified detail in which the parts correspond with those of Fig. 9, with the exception that the metal stay strips are omitted, and to take their places the ends of the end strips 314 are extended and formed with hooks 314*a* adapted to fold inwardly against the outer sides of the side panels 11 and 11' and engage in slots 11*e* in the adjacent portions of the side panels. This has the effect of securing the end strips 314 in upstanding positions and also of bracing the side panels 11 and 11' in upstanding positions.

The body members of these various modified constructions are collapsible to flat form, as first above described, and may be provided with the handle holes F and bottom slots E for attachment of a handle 20 of similar kind.

It is to be understood, however, that other and further modifications of various details of the construction may be made without departing from the scope and spirit of the invention and within the scope of the appended claims.

What I claim is:

1. A collapsible container for carrying bottles or the like comprising a sheet of paper board creased to provide a bottom panel of area to accommodate a plurality of the intended bottles in standing position thereon and side panels flexible to upstanding positions at opposite side margins of the bottom panel, said side panels being

connected to each other at their upper end portions and being creased transversely to permit the container to be collapsed to flattened form with the upper portions of the side panels overlying the upper surface of the bottom panel, the sheet being provided with handle holes spaced from each other transversely of the side panels adjacent their upper ends, and a pre-formed rigid handle having a bail portion with rod-like journals extending toward each other in alignment from its opposite ends, the handle holes being spaced from each other approximately the same distance as are the outer ends of the handle journals and being of size to admit the journals when they are inserted lengthwise only, and the collapsed container being flexible to an arched form to move the handle holes close enough to each other to permit insertion of the handle journals lengthwise through them respectively.

2. A collapsible container for carrying bottles or the like comprising a sheet of paper board creased to provide a bottom panel of area to accommodate a plurality of the intended bottles in standing position thereon and side panels flexible to upstanding positions at opposite side margins of the bottom panel, said side panels being connected to each other at their upper end portions and being creased transversely to permit the container to be collapsed to flattened form with the upper portions of the side panels overlying the upper surface of the bottom panel, the sheet being provided with handle holes spaced from each other transversely of the side panels adjacent their upper ends, and a pre-formed rigid handle having a bail portion with journals extending toward each other in alignment from its opposite ends and of cross-sectional size such as to permit them to be threaded longitudinally through the handle holes, the handle holes being spaced from each other approximately the same distance as are the outer ends of the handle journals, and the collapsed container being flexible to an arched form to move the handle holes close enough to each other to permit insertion of the handle journals through them respectively, the bottom panel being provided with aligned holes underlying the handle holes and of a length approximating that of the respective handle journals.

3. A collapsible container for carrying bottles or the like comprising a sheet of paper board creased to provide a bottom panel of area to accommodate a plurality of the intended bottles in standing position thereon and side panels flexible to upstanding positions at opposite side margins of the bottom panel, said side panels being connected to each other at their upper end portions and being creased transversely to permit the container to be collapsed to flattened form with the upper portions of the side panels overlying the upper surface of the bottom panel, and a pre-formed handle having a bail portion with slender journals extending toward each other from its opposite ends, the sheet being provided with handle holes adjacent the upper ends of the side panels and spaced from each other transversely thereof a distance approximately the same as the spacing of the outer ends of the handle journals, the bottom panel being provided with clearance holes underlying the handle holes, the clearance holes being approximately as long as respective journals and the handle holes being but slightly larger than the cross section of the journals, and the collapsed container being flexible to an arched form to permit insertion of both

journals longitudinally through the handle holes.

4. A collapsible container for carrying bottles or the like comprising a sheet of paper board creased to provide a bottom panel and side panels flexible to upstanding positions at opposite side margins of the bottom panel, said side panels having upper end portions fastened together in overlapped relationship and certain of said panels being creased to permit the container to be collapsed to flattened form, said sheet being provided with handle holes spaced transversely of the side panels in their overlapped upper end portions, and a pre-formed handle having a bail portion with journals extending toward each other from its opposite ends, the outer ends of said journals being spaced approximately the same distance as are said handle holes and the holes being of size to admit the journals when they are inserted endwise only, and the collapsed container being flexible to arched form to move the handle holes sufficiently close to each other to permit insertion of the handle journals longitudinally through respective holes.

5. A knock-down container for carrying bottles or the like comprising a sheet of paper board shaped to provide a bottom panel of area to accommodate a plurality of the intended bottles in standing position thereon and side panels flexible to upstanding positions at opposite side margins of the bottom panel and connected to each other at their upper end portions, said sheet being creased transversely to permit the container to be knocked-down to flattened form, said sheet being provided with handle holes spaced transversely of the side panels in their upper end portions, and a pre-formed handle with a bail portion having parallel legs at its opposite ends and slender journals extending toward each other from the lower ends of said legs, the lower portions of said legs being spaced from each other approximately the same distance as are said handle holes and the holes being of size to admit the journals when they are inserted endwise only, and the container when in flattened condition being flexible to arched form to move the handle holes sufficiently close to each other to permit insertion of the handle journals endwise through respective handle holes to connect the handle to the container.

6. A collapsible container for carrying bottles or the like comprising a sheet of paper board creased to provide a bottom panel of area to accommodate a plurality of the intended bottles in standing position thereon and side panels flexible to upstanding positions at opposite side margins of the bottom panel, said side panels being connected to each other at their upper end portions and being creased transversely to permit the container to be collapsed to flattened form with the upper portions of the side panels over-

lying the upper surface of the bottom panel, and a pre-formed handle having a bail portion with parallel legs at its opposite ends and slender journals extending toward each other from the lower ends of said legs, the sheet being provided with handle holes adjacent the upper ends of the side panels and spaced from each other transversely thereof a distance approximately the same as the spacing of the legs of the handle, the bottom panel being provided with clearance holes underlying the handle holes, the clearance holes being approximately as long as respective journals and the handle holes being but slightly longer than the cross section of the journals, and the collapsed container being flexible to an arched form to permit insertion of both journals longitudinally through the handle holes and clearance holes.

7. In a knock-down holder for packaging bottles and the like, the combination of a flexible body sheet which is formed with side panels which are joined to each other at one end and provided with spaced handle-receiving apertures on their line of juncture, and a stiff pre-formed handle member comprising a bail with journal portions extending toward each other from its ends, the straight line distance between the outer ends of said journal portions being approximately the same as the spacing of the body sheet apertures and the latter being shorter than the journals, and the body sheet being flexible to arched form to bring the handle-receiving apertures close enough together to permit insertion of both journal portions lengthwise through them.

8. A knockdown bottle carrier comprising a flexible sheet of paper board or the like shaped to provide a bottom panel and a pair of conjoined side panels which are flexible to angular relationship relative to each other on a fold line running along their upper ends, said sheet being provided with a pair of handle-receiving holes located approximately on said fold line and spaced from each other lengthwise thereof, and a pre-formed rigid handle having a bail portion with journal portions extending toward each other from its opposite ends, the spacing of the outer ends of said journal portions being approximately the same as the spacing of the handle holes in the sheet, and the size of said holes being such as to permit passage of the journal portions when they are inserted endwise only, the sheet being flexible to an arched form when the carrier is in knocked-down condition, to move the handle holes sufficiently close to each other to permit insertion of the respective journal portions endwise through the respective holes to positions behind the sheet.

HENRY K. POWELL.
